METHOD OF CONTROLLING WEEDS

Llewellyn W. Fancher, Lafayette, Calif., and Chester L. Dewald, Houston, Tex., assignors to Stauffer Chemical Company, New York, N.Y., a corporation of Delaware
No Drawing. Original application May 28, 1963, Ser. No. 283,709, now Patent No. 3,205,253, dated Sept. 7, 1965. Divided and this application July 16, 1965, Ser. No. 484,498

8 Claims. (Cl. 71—2.6)

This is a division of application Serial No. 283,709, filed May 28, 1963, now U.S. Patent No. 3,205,253.

This invention relates to certain new and novel chemical compounds and the use of such compounds as selective herbicides.

More specifically, the invention relates to compounds of the formula:

wherein R_1 and R_2 are lower alkyl radicals. The aryl group in the compounds of the present invention may be either a phenyl group or a substituted phenyl group.

These compounds are prepared by the following reaction:

The beta-chloro intermediates only have been indicated in the above reaction merely for economic reasons. However, the beta-bromo and beta-iodo intermediates will also yield the equivalent phosphate derivatives.

The completeness of the above reaction is dependent upon the type of solvent used. In general, polar solvents are better than non-polar solvents and certain catalysts such as tertiary amines and dimethyl formamide aid in bringing the reaction to completion.

The following non-limiting examples illustrate the preparation of this class of compounds:

Example 1—N-(beta-o,o-diethyldithiophosphorylethyl)-benzene sulfonamide

A mixture of 116 g. (0.53 M) of N-(beta-chloroethyl)-benzene sulfonamide, 162.4 g. (0.8 M) of ammonium-diethyldithiophosphate and 250 ml. of methyl ethyl ketone was stirred and refluxed for four hours. The solvent was removed on a steam bath with an air jet, and the residue taken up in ethyl ether and washed three times with dilute aqueous sodium chloride. The ether solution was dried over anhydrous magnesium sulfate, filtered and the ether removed on the steam bath with an air jet. The viscous product weighed 170 g. (90% of theory). $n_D^{30} = 1.5468$.

Analysis	Sulfur, Percent	Nitrogen, Percent	Phosphorus, Percent
Theory.....	26.00	3.79	8.39
Found.....	25.69	3.88	7.79

Example 2—N-(beta-o,o-diisopropylidithiophosphoryl)-benzene sulfonamide

By an analogous procedure as for Example 1, a mixture of 13.2 g. (0.06 M) of N-(beta-chloroethyl)-benzene sulfonamide, 25.2 g. (0.1 M) of potassium-diisopropyl dithiophosphate and 100 ml. of methyl ethyl ketone

2

yielded after a four hour reflux period, 20.8 g. (88% of theory) of viscous product. $n_D^{30} = 1.5428$.

Analysis	Sulfur, Percent	Nitrogen, Percent	Phosphorus, Percent
Theory.....	24.15	3.54	7.79
Found.....	25.42	3.60	6.72

By analogous procedures the following additional compounds were prepared:

No.	Aryl	R_1 and R_2	n_D^{30}
15	3	Phenyl	1.5377
4	p-Tolyl	ethyl	1.5496
5	do	isopropyl	1.5411
6	p-Chlorophenyl	ethyl	1.5661
7	3,4-dichlorophenyl	do	1.5729
8	do	isopropyl	1.5590
9	2,5-dichlorophenyl	ethyl	1.5685
10	do	isopropyl	1.5595
11	2,5-dimethylphenyl	ethyl	1.5563
12	do	isopropyl	1.5423
13	m-Nitrophenyl	ethyl	1.5708
14	do	isopropyl	1.5501
15	Phenyl	n-Propyl	1.5445
16	2,5-dichlorophenyl	do	1.5583
17	Phenyl	Ethyl-isopropyl	
18	do	Methyl-isopropyl	
19	do	Ethyl-n-propyl	
20	do	Methyl-ethyl	

The compounds of the present invention are excellent herbicides as will be indicated by the test results shown hereinafter wherein the compounds of the present invention are used as pre-emergence herbicides.

In making the tests for pre-emergence application, seeds of the test weed species are planted in individual rows one-half inch deep in Santa Cruz sandy loam soil contained in 8" x 12" metal flats. Enough seeds are planted to give about 30 to 50 plants of each weed species in each flat. The flats are watered after planting and the following day each flat is sprayed at a rate of 5 pounds of the compound under test in 80 gallons of solution per acre. The spraying is conducted as the flat is carried by a moving belt under a sprayer to simulate field spraying conditions. Two weeks later the degree of weed control is determined by comparing the amount of germination and growth of each weed in the treated flats with the weeds in several untreated control flats.

The following chart shows the results of such tests.

Compound	Foxtail		Annual Bluegrass		Crab Grass		Nut Grass	
	Percent Ge	Gr	Percent Ge	Gr	Percent Ge	Gr	Percent Ge	Gr
55	50	1m ₁	100	1m ₁	0	—	0	—
2	50	1m ₁	100	2m ₁	0	—	25	1ch ₁
3	100	5m ₃	100	7	50	2m ₂	—	—
5	50	3m ₃	100	10	50	2m ₂	—	—
6	100	5m ₃	—	—	—	—	—	—
7	100	5m ₃	70	7	—	—	100	10
8	100	5m ₃	100	10	—	—	100	10
10	100	10	100	10	—	—	0	—
13	100	10	30	3	—	—	70	10
14	100	10	100	10	—	—	50	7

Legends: Ge—germination, Gr—growth (on a rating system of 0 to 10; 0=death or very severe effects, 10=normal), m—malformation, ch—chlorosis.

Compounds 15 and 16 were tested slightly differently. In these tests, seeds, of foxtail, annual bluegrass, water grass, and red-root pigweed were planted in individual rows one-half inch deep in Santa Cruz sandy loam soil contained in compressed paper flats 8 1/4" x 6 1/2" which are 2 3/4" deep. Enough seeds are planted to give about thirty to fifty plants of each weed species in each flat.

The flats are watered after planting and the following day each flat is sprayed at a rate of 20 pounds of the compound under test in 80 gallons of solution per acre. A No. 152 DeVilbiss atomizer is used to spray the solution on the soil surface. Two weeks later the degree of weed control is determined by comparing the amount of germination and growth of each weed in the treated flats with the weeds in several control flats.

The results of these tests are as follows:

Compound	Foxtail		Annual Bluegrass		Water grass		Pigweed	
	Percent Ge	Gr	Percent Ge	Gr	Percent Ge	Gr	Percent Ge	Gr
15	0		0		20		2d ₂	
16	50	5	20	b ₂	50	5	20	b ₂

Legends: Ge—germination, Gr—growth (on a 0 to 10 scale; 0=death or very severe effect, 10=normal), b—burn, d—desiccation.

Compounds 17 through 20 were tested in the same manner as were compounds 15 and 16. The test rate, however, was 2 lbs./acre and the weed species tested were crab grass, foxtail and water grass. The results were as follows:

Compound	Crab Grass		Foxtail		Water Grass	
	Percent Ge	Gr	Percent Ge	Gr	Percent Ge	Gr
17	0		0		0	
18	0		0		0	
19	100	2	100	2	100	3
20	100	3	100	5	100	3

Legends: Ge—germination, Gr—growth (on a rating system of 0 to 10; 0=death or very severe effects, 10=normal).

We claim:

1. The method of controlling weeds comprising applying to the soil a herbicidally effective amount of a compound of the formula:

wherein R₁ and R₂ are lower alkyl radicals and X is

selected from the group consisting of hydrogen, chlorine, lower alkyl and nitro.

2. The method of controlling weeds comprising applying to the soil a herbicidally effective amount of the compound N-(beta-o,o-diethylthiophosphorylethyl)-benzene sulfonamide.

3. The method of controlling weeds comprising applying to the soil a herbicidally effective amount of the compound N-(beta-o,o-diisopropylthiophosphorylethyl)-benzene sulfonamide.

4. The method of controlling weeds comprising applying to the soil a herbicidally effective amount of the compound N-(beta-o,o-diisopropylthiophosphorylethyl)-2,5-dichlorobenzene sulfonamide.

5. The method of controlling weeds comprising applying to the soil a herbicidally effective amount of the compound N-(beta-o,o-di-n-propylthiophosphorylethyl)-benzene sulfonamide.

6. The method of controlling weeds comprising applying to the soil a herbicidally effective amount of the compound N-(beta-o,o-di-n-propylthiophosphorylethyl)-2,5-dichlorobenzene sulfonamide.

7. The method of controlling weeds comprising applying to the soil a herbicidally effective amount of the compound N-(beta-o-ethyl-o-isopropylthiophosphorylethyl)-benzene sulfonamide.

8. The method of controlling weeds comprising applying to the soil a herbicidally effective amount of the compound N-(beta-o-methyl-o-isopropylthiophosphorylethyl)-benzene sulfonamide.
